UNITED STATES PATENT OFFICE.

STILLWELL R. HAROURT, OF CHICAGO, ILLINOIS, ASSIGNOR TO W. W. KIMBALL COMPANY, OF CHICAGO, ILLINOIS, A CORPORATION OF ILLINOIS.

MUSIC-SHEET GUIDE.

1,399,114.

Specification of Letters Patent.

Patented Dec. 6, 1921.

Application filed March 21, 1921. Serial No. 453,913.

To all whom it may concern:

Be it known that I, STILLWELL R. HAROURT, a citizen of the United States, residing at Chicago, in the county of Cook and State of Illinois, have invented certain new and useful Improvements in Music-Sheet Guides, of which the following is a specification.

This invention relates to devices for automatically maintaining the music record sheet of a player piano or like instrument in correct register with the tracker range of the instrument. Devices of this character, commonly known in the trade as "tracker devices" or "trackers" have heretofore, so far as I am aware, involved the use of separate motors to effect an endwise shift of either the delivery or receiving roll or the tracker-bar when the sheet creeps out of proper register; and these motors have usually been controlled either by the sheet itself in conjunction with special holes in the tracker-bar, or by mechanical devices operated by one or both edges of the sheet. Such tracker devices are complicated and expensive to manufacture, and more or less faulty in action and liable to derangement.

The main object or purpose of my present invention is to provide a music sheet guide or tracker device that shall be very simple in construction, purely mechanical in character, reliable and efficient in action, and of very low cost. Another object is to provide a music sheet guide of such a nature and construction that it can readily be applied to any standard make of player piano or other pneumatically operated musical or other instrument without involving any substantial change in or alteration of the instrument itself. Another object is to provide a music sheet guide that will not involve any bodily endwise shifting of either of the spools or the tracker bar and consequently will not require the use of a motor or motors to effect such shifting. A still further object is to provide a device that will cause the sheet to be snugly rewound on the delivery roll.

It is well known that the paper record sheets vary considerably in width according to climatic and weather conditions. In damp weather the sheets expand widthwise, and in dry weather they contract. Hence, it is necessary to make the body of the receiving spool of such a length (between its

heads) as will accommodate the sheet in its widest condition, since otherwise the edges of the sheet will curl or bend up as the sheet is wound on the spool, and the coils will not lie in close and compact condition. But this allows a narrow sheet to creep edge-wise sufficiently to get out of correct register with the tracker-bar and produce discord in the music; and hence has arisen the necessity of providing some means for automatically maintaining a correct registration of the sheet with the tracker-bar. It has heretofore been proposed to secure this result by making one head of the receiving spool slidable endwise of the body of the spool and spring-pressed inwardly, so that in the innermost position of the slidable head the spool will just fit a record sheet in its narrowest (dry) condition, and when a wider (damp) sheet is wound thereon the sheet itself forces the slidable head outwardly. This scheme, however, has not been found practicable, for the reason that it throws on the thin edge of the sheet the whole burden of forcing the head outwardly against its spring, and this results in a curling of the edge and faulty winding of the sheet on the spool. In my present invention I employ a movable head on the receiving spool; but instead of making it inwardly spring-pressed I may leave it free, but preferably make it outwardly spring-pressed, and it is very gradually forced inwardly, as the winding of the sheet on the receiving spool progresses, by a shoe or shoes bearing on the continually increasing roll of paper on the receiving spool and operating through suitable connections, to press said movable head inwardly against the end of the wound roll on the spool.

My invention, its operative principle, and the advantages inherent therein will all be readily understood and appreciated by those skilled in the art as the same becomes better understood from the following detailed description, taken in connection with the accompanying drawings wherein I have illustrated one practical and workable embodiment of the invention, and in which:

Figure 1 is a front elevation, partly in vertical section, of the delivery and receiving spools, tracker-bar, and music record sheet of a player piano equipped with my improved music sheet guide or tracker device;

Fig. 2 is a vertical section on the line 2—2 of Fig. 1; and

Fig. 3 is a vertical section enlarged on the line 3—3 of Fig. 2.

5 Referring to the drawings—

5 designates the top bar, 6 the bottom bar, and 7 the side bars of a rectangular frame or casing, in the side bars 7 of which, and in brackets 8 and 9 attached thereto, are mounted the chucks 10 and 11 of the delivery spool 12 and the chucks 13 and 14 of the receiving spool 15. 16 designates the tracker-bar, and 17 the perforated music record sheet. These parts except the receiving spool 15 are all 10 of usual and well known construction, and need not be more particularly described herein.

The receiving spool has one head 18 that is rigid with the body, while the other head 19 is attached to the body in such a manner as to have a limited in and out movement relatively thereto. As herein shown the head 19 is slidably mounted on a plurality of screws 20 entered in the adjacent end of the 15 spool body and its central boss 21 is likewise slidably on the spindle or pintle 22 of the spool. The end of the spool body is chambered around the screws 20, as shown at 23 in Fig. 3, to form housings for light coil 25 springs 24 that press the head 19 outwardly or away from the end of the body to the extent permitted by the heads of the screws.

Through the lower frame bar 6 are formed 20 a pair of countersunk holes 25 in which is 30 slidably mounted a U-shaped member 26 that constitutes a support or carrier for a pair of shoes 27 mounted on the upper ends of the side limbs of the support 26. These shoes are lightly pressed against the body of the 35 spool 15 by the following described mechanism. Attached to or forming a part of the bracket 9 is a strip or plate 28 to which is pivoted at 29 a lever, the longer bent arm 40 30 of which extends beneath the frame bar 30 and has an up-turned end 31 apertured to 45 loosely and flexibly articulate with the transverse limb of the shoe carrier 26. Attached to the lever arm 30 is a tension spring 32, the other end of which is anchored to the frame 50 bar 6; said spring tending to raise the arm 30 and consequently the shoe support and shoes. The shorter arm 33 of the lever has a 55 forked upper end which straddles a thrust rod 34 slidably mounted in the frame bar 7 60 and in a bracket 35 attached to the latter. The rod 34 has a downwardly turned forked inner end 36 that straddles the spool chuck 13 and lies in contact with the boss 21 of the movable head 19. Loose on the rod 34 is a 65 washer 37 that is pressed against the forked end of the lever arm 33 by a compression 70 spring 38 which abuts against a collar 39 adjustably keyed on the rod 34. By means of the spring 38 the lever arm 33 imparts an 75 elastic yieldable push to the thrust rod 34

and through the latter to the spool head 19. A stop collar 40 keyed to rod 34 on the opposite side of the lever arm 33 co-operates with the bracket 35 to limit the swinging movement of the lever under the pull of 80 spring 32.

It is believed that the operation of the device as an automatic music sheet guide or tracker will be apparent from the foregoing description of its construction and organization, but the same may be briefly outlined as follows. The lower end of the record sheet is hooked to the receiving spool in the usual manner, with the right hand edge of the sheet lying against the inner face of 85 the fixed head 18. If the sheet is narrower than the distance between the inner faces of the two heads, there will be, of course, at the start a slight space or clearance between the left hand edge of the sheet and the inner 90 face of the movable head 19. As the winding up of the sheet on the receiving spool proceeds, during the playing of the record, the shoes 27 and their support or carrier 26 are gradually forced downwardly, thereby 95 exerting an inward thrust on the head 19, bringing the latter into contact with the left hand edge of the wound up portion of the sheet on the spool, as indicated in Fig. 3; and since the pressure or thrust of the 100 head is resisted by a closely rolled or wound body of the record sheet, no curling or bending over of the edge of the sheet occurs, and the two heads are thus automatically spaced to the exact width of the sheet, and no edge-wise creeping of the sheet can occur. When the movable head has thus been brought 105 squarely into contact with the wound portion of the sheet on the spool, no further movement of the head takes place; but the further swinging of the lever, as the wound roll increases in diameter, is permitted by the yielding and compression of the spring 38.

A single shoe may be used in lieu of the 110 pair of shoes shown and described, but the latter arrangement is preferred because better distributing the slight frictional drag on the sheet and promoting greater uniformity in the winding. Moreover, in the construction shown the two shoes are equally balanced on the end of the lever arm 30 so that they exert exactly equal pressures on the receiving spool.

During rewinding the shoes 27 serve 115 another important and useful function in applying a light friction drag or back pull to the sheet, which keeps the latter taut and causes it to be snugly rewound, thus eliminating the slack that usually exists in 120 the roll on the delivery spool and which makes it necessary to give the spool several turns in the roll to remove the slack before placing the roll in the instrument.

It is manifest that the mechanism shown 125

and described herein may be variously modified in respect of details of structure and arrangement without involving any departure from its operative principle or sacrificing any of the advantages thereof. Hence, I reserve all such variations and modifications as fall within the spirit and purview of the appended claims.

I claim:

- 10 1. In a music sheet guide for player pianos and the like, the combination with a receiving spool having a movable head, of a mechanism actuated by the portion of the music sheet roll on said receiving spool for pressing said movable head inwardly as the sheet is wound on said receiving spool.
- 15 2. In a music sheet guide for player pianos and the like, the combination with a receiving spool having a movable head, of spring means urging said movable head outwardly from the end of the spool body, and mechanism actuated by the portion of the music sheet roll on said receiving spool for pressing said movable head inwardly as the sheet is wound on said receiving spool.
- 20 3. In a music sheet guide for player pianos and the like, the combination with a receiving spool having a movable head, of a shoe spring-pressed against the body of said receiving spool, a movable support for said shoe, and actuating connections between said support and said movable head through which, as the music sheet is wound on said receiving spool, said movable head is pressed inwardly.
- 25 4. In a music sheet guide for player pianos and the like, the combination with a receiving spool having a movable head, of spring means urging said movable head outwardly from the end of the spool body, a shoe spring-pressed against the body of said receiving spool, a sliding support for said shoe, and actuating connections between said support and said movable head through which, as the music sheet is wound on said receiving spool, said movable head is pressed inwardly.
- 30 5. In a music sheet guide for player pianos and the like, the combination with a receiving spool having a movable head, of spring means urging said movable head outwardly from the end of the spool body, a slidably mounted U-shaped shoe support, a pair of shoes on the upper ends of the side limbs of said support respectively and bearing against the body of said spool, and actuating connections between the transverse limb of said shoe support and said movable head through which an outward movement of said shoes relatively to the spool body transmits an inward thrust to said movable head.
- 35 6. In a music sheet guide for player pianos and the like, the combination with a receiving spool having a movable head, of spring means urging said movable head outwardly from the end of the spool body, a slidably mounted U-shaped shoe support, a pair of shoes on the upper ends of the side limbs of said support respectively and bearing against the body of said spool, a pivoted lever at one end engaged with the transverse limb of said shoe support and at its other end engaged with said thrust member, and a spring urging said shoes against said receiving spool.
- 40 7. In a music sheet guide for player pianos and the like, the combination with a receiving spool having a movable head, of spring means urging said movable head outwardly from the end of the spool body, a slidably mounted U-shaped shoe support, a pair of shoes on the upper ends of the side limbs of said support respectively and bearing against the body of said spool, a pivoted lever at one end engaged with the transverse limb of said shoe support and at its other end engaged with said thrust member, and a spring urging said shoes against said receiving spool.
- 45 8. In a music sheet guide for player pianos and the like, the combination with a receiving spool having a movable head, of spring means urging said movable head outwardly from the end of the spool body, a slidably mounted U-shaped shoe support, a pair of shoes on the upper ends of the side limbs of said support respectively and bearing against the body of said spool, a pivoted lever at one end engaged with the transverse limb of said shoe support and at its other end having a spring thrust connection to said thrust member, and a spring acting on said lever to cause it to press said shoe support and shoes toward said receiving spool.
- 50 9. In a music sheet guide for player pianos and the like, the combination with a receiving spool having a movable head, of spring means urging said movable head outwardly from the end of the spool body, a slidably mounted U-shaped shoe support, a pair of shoes on the upper ends of the side limbs of said support respectively and bearing against the body of said spool, a pivoted lever at one end flexibly articulated to the transverse limb of said shoe support and at its other end having a spring thrust connection to said thrust member, and a spring acting on said lever to cause it to press said shoe support and shoes toward said receiving spool.
- 55 10. In a music sheet guide for player pianos and the like, the combination with a receiving spool having a movable head, of spring means urging said movable head outwardly from the end of the spool body, a slidably mounted U-shaped shoe support, a pair of shoes on the upper ends of the side limbs of said support respectively and bearing against the body of said spool, a pivoted lever at one end flexibly articulated to the transverse limb of said shoe support and at its other end having a spring thrust connection to said thrust member, and a spring acting on said lever to cause it to press said shoe support and shoes toward said receiving spool.
- 60 11. In a music sheet guide for player pianos and the like, the combination with a receiving spool having a movable head, of spring means urging said movable head outwardly from the end of the spool body, a slidably mounted U-shaped shoe support, a pair of shoes on the upper ends of the side limbs of said support respectively and bearing against the body of said spool, a pivoted lever at one end flexibly articulated to the transverse limb of said shoe support and at its other end having a spring thrust connection to said thrust member, and a spring acting on said lever to cause it to press said shoe support and shoes toward said receiving spool.

and the like, the combination with a receiving spool having a movable head, of spring means urging said movable head outwardly from the end of the spool body, a slidably mounted U-shaped shoe support, a pair of shoes on the upper ends of the side limbs of said support respectively and bearing against the body of said spool, a pivoted lever at one end flexibly articulated to the transverse limb of said shoe support and at its other end having a spring thrust connection to said thrust member, and a spring acting on said lever to cause it to press said shoe support and shoes toward said receiving spool.

7. In a music sheet guide for player pianos and the like, the combination with a receiving spool having a movable head, of spring means urging said movable head outwardly from the end of the spool body, a slidably mounted U-shaped shoe support, a pair of shoes on the upper ends of the side limbs of said support respectively and bearing against the body of said spool, and actuating connections between the transverse limb of said shoe support and said movable head through which an outward movement of said shoes relatively to the spool body transmits an inward thrust to said movable head.

8. In a music sheet guide for player pianos and the like, the combination with a receiving spool having a movable head, of spring means urging said movable head outwardly from the end of the spool body, a slidably mounted U-shaped shoe support, a pair of shoes on the upper ends of the side limbs of said support respectively and bearing against the body of said spool, a pivoted lever at one end engaged with the transverse limb of said shoe support and at its other end engaged with said thrust member, and a spring urging said shoes against said receiving spool.

9. In a music sheet guide for player pianos and the like, the combination with a receiving spool having a movable head, of spring means urging said movable head outwardly from the end of the spool body, a slidably mounted U-shaped shoe support, a pair of shoes on the upper ends of the side limbs of said support respectively and bearing against the body of said spool, a pivoted lever at one end engaged with the transverse limb of said shoe support and at its other end having a spring thrust connection to said thrust member, and a spring acting on said lever to cause it to press said shoe support and shoes toward said receiving spool.

STILLWELL R. HARCOURT.
